[57] CLAIM

The ornamental design for a feed roll for seed planter, as shown and described.

DESCRIPTION

FIG. 1 is a perspective view of a feed roll for seed planter showing my new design;

FIG. 2 is a perspective view of the side opposite that shown in FIG. 1;

FIG. 3 is a side elevational view thereof;

FIG. 4 is a side elevational view showing the side opposite that shown in FIG. 3;

FIG. 5 is an elevational view as viewed from the left side of FIG. 3;

FIG. 6 is an elevational view as viewed from the right side of FIG. 3;

FIG. 7 is a top plan view looking down on FIG. 3; and,

FIG. 8 is a bottom view thereof.
